J. BOOGAARD.

HANDY OIL CAN.

APPLICATION FILED JUNE 12, 1917.

1,285,606.

Patented Nov. 26, 1918.

UNITED STATES PATENT OFFICE.

JOHANNES BOOGAARD, OF GRANGEVILLE, IDAHO.

HANDY OIL-CAN.

1,285,606.

Specification of Letters Patent. Patented Nov. 26, 1918.

Application filed June 12, 1917. Serial No. 174,314.

To all whom it may concern:

Be it known that I, JOHANNES BOOGAARD, a citizen of the United States, residing at Grangeville, in the county of Idaho, State 5 of Idaho, have invented certain new and useful Improvements in Handy Oil-Cans; and I do hereby declare the following to be a full, clear, and exact description of the invention, such as will enable others 10 skilled in the art to which it appertains to make and use the same.

This invention relates to new and useful improvements in oil cans, and has for its primary object to provide an oil can in 15 which the oil is forced from the can under pressure.

Referring to the drawings,

Figure 1 is a view in elevation of the can, Fig. 2 is a vertical sectional view thereof, 20 Fig. 3 is a detail view of a portion of the device,

Fig. 4 is a detail view of another portion of the device, and,

Fig. 5 is a longitudinal sectional view 25 showing one of the operating positions of the device.

Referring more particularly to the drawings, the device comprises a receptacle 10 the top of which is provided with an annular flange 11 which is adapted to be 30 closed by a screw threaded plug 12.

Rigidly carried by this screw threaded plug and extending to a point near the bottom of the receptacle 10 is a tubular member 13, and this tubular member is provided with a reduced tubular extension 14 which is removably secured to said tube by means of a coupling 15 as shown in Fig. 3.

The coupling is provided with a reduced 40 passage way 16 and pivotally mounted as at 17 and adapted to close said reduced passage 16. is a valve member 18. This tubular member 13 projects above the screw threaded plug 12 as at 19 and in said projecting portion, the tubular member 13 is 45 provided with diametrically opposite slots 20 for a purpose to be hereinafter described.

Slidably mounted within the tubular member 13, is a tubular member 22 the upper end of which is provided with a discharge spout 23 which is reduced relative 50 to the tube 22, and at the base of said reduced portion there is formed a shoulder 24. Mounted upon the shoulder 24 is an 55 operating handle 25 the ends 26 of which

are adapted to pass through the diametrically opposite slots 20, and this handle 25 forms means by which the tubular member 22 is reciprocated longitudinally of the tubular member 13. The tubular member 60 22 is provided at its lower ends with a valve seat 30 which in turn is provided with a central passage 31 and pivoted as at 32 to said valve seat is a valve member 33 which is adapted to close the opening 31. 65 Slidably mounted in the tubular member 13 is a pump piston 35, and interposed between the top edge of the coupling 15 and said piston 35 is a coil spring 36.

The operation of the device is as follows:—

The receptacle is held in the hand with the handle 25. If now pressure be exerted upon the handle 25 it will be seen that the tubular member 22 will be moved longitudinally of the tubular member 13 which action opens the valve 33 and permits of a passage of oil through said valve into the tubular member 22. When the operating handle 25 is released the tubular member 70 22 is forced longitudinally of the tubular member 13 under the influence of the coil spring 36, and this movement causes the piston 35 to suck the oil through the pipe 14 and the valve 18 into the lower end of 75 the tubular member 13 where said oil is contained. The oil will be forced through the valve opening 31 and discharged through the spout 23.

Having thus described the invention 80 what is claimed is,

1. An oil can comprising a receptacle, an outer stationary tubular member mounted therein, a valve normally closing the inner end of said tubular member, a coupling 95 connected to the inner end of said tubular member, a tubular extension carried by said coupling and extending exteriorly and longitudinally of said tubular member and toward its outer end, an inner tubular 100 member slidably mounted in said outer tubular member, and a valve controlling the inner end of the inner tubular member and adapted to open to admit a liquid into the inner tubular member when the same is 105 slid inwardly.

2. An oil can comprising a receptacle, an outer stationary tubular member mounted therein, a valve normally closing the inner 110 end of said tubular member, a coupling

connected to the inner end of said tubular member, a tubular extension carried by said coupling and extending exteriorly and longitudinally of said tubular member, an
5 inner tubular member slidably mounted in said outer tubular member, a valve controlling the inner end of the inner tubular member and adapted to open to admit a liquid into the inner tubular member when
10 the same is slid inwardly, and a spring in-

terposed between said coupling and the inner end of said inner tubular member to normally force the same outwardly.

In testimony whereof, I affix my signature in the presence of two witnesses.

JOHANNES BOOGAARD.
